UNITED STATES PATENT OFFICE.

JOHN MORRISON, JR., OF GLENS FALLS, NEW YORK.

BRUSH.

1,347,648.

Specification of Letters Patent.

Patented July 27, 1920.

Application filed February 4, 1920. Serial No. 356,194.

To all whom it may concern:

Be it known that I, JOHN MORRISON, Jr., a citizen of the United States, residing at Glens Falls, in the county of Warren and 5 State of New York, have invented certain new and useful Improvements in Brushes, of which the following is a full, clear, and concise description.

My invention relates to brushes, and more 10 particularly to brushes of various types used, mostly by hand, for polishing shoes, brushing clothes, grooming horses, removing crumbs from tables, etc.

By my invention I seek to make a brush 15 provided with a back made of sheet metal and containing a moldable material or cement for holding the bristle tufts, the brush as a whole being comparatively light and strong, and adapted to be made up at a 20 relatively small cost.

In the past many manufacturers have endeavored to market a brush of the general type here contemplated and having a metal back and a cement filling contained therein 25 for holding the bristles. Such brushes, however, have not been very successful, the chief objection being that they were heavy owing to the weight of the cement carried. It was necessary to employ enough cement 30 or other moldable material to properly secure the bristle tufts in position and also to get a good anchorage as between the metal backs and the filling, and thus the amount of filling material used rendered the brush 35 rather too heavy for general satisfaction. What I seek to do, therefore, is to make a brush having a metal back and a cement facing for holding the bristles, the quantity of cement used, however, being relatively 40 small. I accomplish these results by using a wooden core in connection with the cement as virtually a part of the filling, and by securing the wooden core directly to the metallic portion of the brush back, so as to 45 avoid the necessity for anchoring the cement directly to the metallic portion of the brush back.

Reference is made to the accompanying drawings forming a part of this specification, and in which like reference characters 50 indicate like parts throughout the several figures.

Figure 1 is a side view of my improved brush, showing the same partly in elevation 55 and partly as broken away.

Fig. 2 is an inverted plan view of the metallic shell of the brush back, with one form of the wooden core mounted therein.

Fig. 3 is a view partly in plan and partly broken away, showing the parts appearing 60 in Fig. 2.

Fig. 4 is an inverted plan, somewhat similar to Fig. 2, but showing another form of core and different means for securing the same to the shell. 65

Fig. 5 is a longitudinal section through the parts shown in Fig. 4.

Fig. 6 is an inverted plan showing the metallic shell having the wooden core secured therein in a different manner from 70 that indicated in other figures, the core being shown as partly broken away.

Fig. 7 is a longitudinal section through the parts shown in Figs. 6, the core appearing as partly broken away. 75

Fig. 8 is a section on the line 8—8 of Fig. 7, looking in the direction indicated by the arrows.

The metallic shell is shown at 9, and is 80 preferably stamped or pressed out of a single integral piece of sheet metal. It is provided with side portions 9^a and end portions 9^b which are thus integral with it. The side portions 9^a may be strictly parallel with each other, and this is also true of the end 85 portions 9^b. That is to say, it is not necessary that the side portions or the end portions of the shell be inclined relatively to each other, for the reason that the shape of the shell need not be relied upon for the 90 purpose of holding the cement and other parts in position, as hereinafter described.

One form of wooden core, to be secured within the metallic shell is shown at 10, and has in this instance the form of a flat, thin 95 block. Secured to this wooden core are a pair of fastening strips 11, held in position by pins or nails 12.

A slightly different form of wooden core is shown at 10^a, in Fig. 4, and is similarly 100 provided with fastening strips 11^a.

The fastening strips 11 and 11^a are secured firmly upon the inner surface of the metallic shell by means of solder 13, which may be applied either by hand or by aid of 105 a soldering machine.

The fastening strip 11^a is provided with face grooves 14 and with edge grooves 15, and thus given an articulate surface.

In Fig. 6 is a wooden core 10^b differing 110

slightly from those shown at 10 and 10^a. The core 10^b carries a pair of wire staples 16 provided with bends 16^a and secured to the inner surface of the shell by solder 17.

5 A filling 18, made of cement or other moldable material, occupies all the space in the shell except such as is occupied by the wooden core. The bristle tufts are shown at 19, and are severally held in position by 10 being partially embedded in the cement.

The cement is poured or pressed into the shell in a manner well known in this art, and which I do not deem it necessary to describe. The adhesion between the cement and the 15 wooden core is ordinarily sufficient to hold them together firmly, even in instances where the core is smooth as in Fig. 2. However, if desired there is nothing to prevent the wooden core from being provided with 20 the grooves 14 and 15 above described, or otherwise provided with such articulate surface as will improve the holding qualities of the core relatively to the cement.

It will be noted that since the cement 25 adheres to the core there is no need for any special provision to use the form of the shell as a means for effectively anchoring the cement to the shell.

It is a fact well known in this art that if 30 a brush back be filled to any considerable depth with cement the brush as a whole is necessarily quite heavy, as elsewhere stated, and yet in order to obtain a sufficient anchorage between the metallic shell and the 35 cement, in the manner in which these parts have heretofore been made, it has been necessary to make the cement comparatively thick. Moreover the cement does not adhere to the metal back, and shrinks away 40 from the latter in cooling, so as to become loose unless supported by an undercut formed in the shell. Again, cement thus used is very brittle, so that if the brush containing it as prepared in the usual manner 45 happens to fall, specially with the cement slightly loose in the shell, the cement filling is apt to be broken. My invention above described overcomes the difficulties just stated.

50 I do not limit myself to the precise construction shown and described, the scope of my invention being commensurate with my claims.

Having thus described my invention, what I claim as new and desire to secure by Letters Patent is as follows:

1. In a brush the combination of a shell, a wooden core housed within said shell, metallic fastening members secured to said shell and also secured to the inner surface of 60 said core, a cement filling housed within said shell and engaging said core, and bristle tufts supported by said cement filling.

2. In a brush the combination of a metallic shell, a core located within said metallic shell, a plurality of fastening strips secured to said core and soldered directly to the inner surface of said shell, a cement filling housed within said shell and adhering directly to said core and supported thereby 70 independently of any adhesion between said cement filling and said shell, and bristle tufts carried by said cement filling and extending therefrom.

3. A brush comprising a shell made of 75 thin sheet metal, a wooden core located within said shell and having the form of a flat block, fastening strips made of thin sheet metal and soldered directly to the inner surface of said shell, a cement filling housed 80 within said shell and having an outer face located in proximity to one face of said core so as to render said filling comparatively thin, bristle tufts each partially embedded within said cement filling and extending 85 therefrom, and metallic fastening members holding said fastening strips firmly upon said core.

4. In a brush the combination of a shell made of thin sheet metal and having a longitudinal form, a pair of thin metallic fastening strips located within said shell and soldered thereto at points adjacent the ends thereof, said metallic strips being disconnected from each other, a core made of light 95 material and housed within said shell, said core being secured directly to said fastening strips, a filling of moldable material housed within said shell and enveloping said core so as to adhere directly thereto independently of any adhesion between said core and said shell, and a plurality of bristle tufts carried by said filling and projecting therefrom.

JOHN MORRISON, JR.
